UNITED STATES PATENT OFFICE.

BENNETT D. STRAIGHT, OF DETROIT, MICHIGAN, ASSIGNEE TO MAIL-OM-ETER COMPANY, OF DETROIT, MICHIGAN, A CORPORATION OF MICHIGAN.

STAMP-DELIVERY MECHANISM.

1,127,543.

Specification of Letters Patent. Patented Feb. 9, 1915.

Application filed October 9, 1909. Serial No. 521,898.

To all whom it may concern:

Be it known that I, BENNETT D. STRAIGHT, a citizen of the United States of America, residing at Detroit, in the county of Wayne and State of Michigan, have invented certain new and useful Improvements in Stamp-Delivery Mechanisms, of which the following is a specification, reference being had therein to the accompanying drawings.

10 The invention relates to stamp feeding or delivery mechanism, and is more particularly designed for use in connection with stamp-affixing machines.

It is the object of the invention to obtain 15 a construction in which the feeding or delivery of the stamp will at the same time place an identification mark upon each stamp fed or delivered.

It is a further object to produce the desired result with a simple construction of 20 mechanism, and the invention consists in the construction as hereinafter set forth.

In the drawings, Figure 1 is a horizontal section through an envelop sealing, stamping and delivery mechanism to which my 25 improvements are applied; Fig. 2 is a side elevation of the feed mechanism; Fig. 3 is a top plan view thereof; and Fig. 4 is a section on line $x-x$ of Fig. 2.

30 In order to detect theft or fraud, it is frequently desirable to place upon postage stamps an identification mark, and machines have heretofore been devised for this purpose.

35 My invention broadly consists in associating a means for producing the identification mark with a feeding or delivery mechanism for the stamps, thereby obtaining a construction adapted to be incorporated as 40 a part of my stamp-affixing machine, or an envelop sealing and stamp-affixing machine, or for any other construction in which the stamps are successively delivered.

In the drawing, I have shown merely the 45 one application—intended for an envelop sealing and stamping machine, but I do not wish to limit my invention to this one use.

As shown, A and B are the co-operating rolls for sealing and stamping the envelopes, 50 which are delivered to said rolls by suitable mechanism (not shown). C D E are small rolls associated with the roll A for moistening and delivering the stamp to the envelop, and F is the cutter for severing the stamps 55 from the strip. These parts may be of any

suitable construction, operated by mechanism not shown.

The stamps fed to the rolls C and D are in the form of a continuous strip, which is intermittently advanced a determined amount, so as to bring the line of division between successive stamps in exact registration with the severing blade. For this purpose I preferably employ a main feed, which advances the stamps approximately the required amount, and a correcting feed that compensates for slight differences in the spacing, due to the expansion or contraction of the paper, and secures the exact registration desired. The correcting feed may be of any suitable construction, but as shown 70 comprises a plurality of pawls G having needle points G' which in the movement of the pawl will drop into the perforations between adjacent stamps. These pawls are 75 actuated alternately with the main feed, and wherever the latter fails to advance the stamp the full amount the points G' will be engaged with the perforations before the pawls G reach the limit of their movement, 80 and the strip will be further advanced to the proper position.

For placing the identification mark upon the stamps, an automatic marker is associated with the feed mechanism and operates upon the strip after each movement of advancement. As shown, this automatic marker is also employed for the further function of feeding the strip. Specifically, it consists of a die plate H and a punch I, 90 preferably provided with a series of needle punches I' arranged to form a letter, numeral, or other identification mark. The needles are normally separated from the die plate to permit the passage of the stamp strip J therebetween, but periodically the punch is moved inward, causing the perforation of the strip by the needles which pass into the die plate. While thus engaged, both the die plate and punch are advanced, 100 so as to cause the feeding of the strip, after which the punch is again retracted while the strip is held by a stripper plate K.

For operating the punch, a die mechanism is provided which as shown is of the 105 following construction: L is an eccentric rotating with the roll A and arranged at the upper end thereof. M is a rod connecting the eccentric L with a slide N traveling upon a guide O. P is a lever fulcrumed at 110

16 P' upon the slide N, and carrying at its free end the punch member I, while the opposite end of the lever extends into proximity to a pair of opposed set-screws Q engaging the end of the eccentric rod M. The arrangement is such that in the rotation of the eccentric L, longitudinal movement of the rod M will carry with it the slide N and lever P mounted thereon, while the lateral or angular movement of the rod M will rock said lever upon its fulcrum and cause the insertion and withdrawal of the punch from the die.

17 In the operation of the machine, each reciprocal motion of the slide will cause, first, the engagement of the punch with the die perforations and stamp, and then to follow it by the strip that is being advanced. At the completion of the forward movement, the punch is withdrawn from engagement with the perforations, permitting the correcting feed to operate, bringing the strip into proper position for a succeeding operation by the main feed. Each time the punch

operates it will form an identification mark 25 in the stamp, and as an individual character is placed on each machine the subsequent inspection of the stamp will reveal the proper machine employed in its delivery.

What I claim as my invention is:

1. In a stamp delivery mechanism, associated means constituting a main feed and a correcting feed for the stamp strip, and an engaging device for one of said feeds forming an indented identification mark on the 35 stamps.

2. In a stamp delivery mechanism, means for feeding a strip of stamps including a strip-engaging device forming a part of said feeding means and adapted to place a predetermined indented identification mark upon each stamp.

In testimony whereof I affix my signature in presence of two witnesses.

BENNETT D. STRAIGHT.
